UNITED STATES PATENT OFFICE

JOHN F. MEYER, OF PASADENA, CALIFORNIA

DESIGN FOR AN AMUSEMENT MACHINE CABINET

Application filed August 26, 1932. Serial No. 44,698. Term of patent 7 years.

To all whom it may concern:

Be it known that I, JOHN F. MEYER, a citizen of the United States, residing at Pasadena, in the county of Los Angeles and State of California, have invented a new, original, and ornamental Design for an Amusement Machine Cabinet, of which the following is a specification, reference being had to the ac-

companying drawing, forming a part thereof, in which the figure is a perspective view of an amusement machine cabinet showing my new design.

I claim:

The ornamental design for an amusement machine cabinet as shown.

JOHN F. MEYER.
